Primary Examiner — Doris Clark(74) *Attorney, Agent, or Firm* — The Weintraub Group, P.L.C.(57) **CLAIM**

I claim the ornamental design for a scroll trellis, as shown and described.

DESCRIPTION

FIG. 1 is a front elevational view of the scroll trellis showing my new design, the rear view of the scroll trellis being a minor image of the front view;

FIG. 2 is a first side elevational view thereof, the second side elevational view of the scroll trellis as seen from the side opposite that of FIG. 2 being a mirror image of FIG. 2;

FIG. 3 is a top plan view thereof; and,

FIG. 4 is a bottom plan view thereof.
